[57] CLAIM

The ornamental design for a oxygen concentrator, as shown and described.

DESCRIPTION

FIG. 1 is a right side perspective view of an oxygen concentrator showing my new design;

FIG. 2 is a left side perspective view thereof;

FIG. 3 is a right side elevational view thereof;

FIG. 4 is a front side elevational view thereof;

FIG. 5 is a left side elevational view thereof;

FIG. 6 is a rear side elevational view thereof; and

FIG. 7 is a top plan view thereof.

The broken line showing of a cord and plug is for illustrative purposes only and forms no part of the claimed design.

FIG. 1
